UNITED STATES PATENT OFFICE.

ALEXIUS P. FLECKENSTEIN, OF IONIA, MICHIGAN, ASSIGNOR TO FLECKENSTEIN
VISIBLE GASOMETER CO. OF MICHIGAN, OF GRAND RAPIDS, MICHIGAN, A COR-
PORATION OF MICHIGAN.

DESIGN FOR A LIQUID-DISPENSING APPARATUS.

Application filed June 5, 1924. Serial No. 9,804. Term of patent 14 years.

To all whom it may concern:

Be it known that I, ALEXIUS P. FLECKENSTEIN, a citizen of the United States, residing at Ionia, in the county of Ionia and State of Michigan, have invented a new, original, and ornamental Design for Liquid-Dispensing Apparatus, of which the following is a specification, reference being had to the accompanying drawing, forming part thereof.

The figure is a perspective view of a liquid dispensing apparatus showing my new design.

I claim:

The ornamental design for a liquid dispensing apparatus as shown.

ALEXIUS P. FLECKENSTEIN.
